UNITED STATES PATENT OFFICE.

LOUIS ZEVIN AND HARRY ZEVIN, OF NEW BRITAIN, CONNECTICUT.

CURTAIN AND SHADE-ROLLER SUPPORTER.

1,147,354.

Specification of Letters Patent.

Patented July 20, 1915.

Application filed June 20, 1913, Serial No. 774,803. Renewed June 15, 1915. Serial No. 34,301.

To all whom it may concern:

Be it known that we, LOUIS ZEVIN and HARRY ZEVIN, citizens of the United States, residing at New Britain, in the county of 5 Hartford and State of Connecticut, have invented certain new and useful Improvements in Curtain and Shade-Roller Supporters, of which the following is a specification.

10 Our invention relates to improvements in curtain and shade roller supporters, and the object of our improvement is simplicity and economy in construction and convenience and efficiency in use.

15 In the accompanying drawing:—Figure 1 is a front elevation of our improved curtain and shade roller holder, and a shade roller, a curtain pole, and part of a window casing. Fig. 2 is a front elevation on an enlarged scale of the left hand curtain and shade roller holders. Fig. 3 is an end elevation of the same. Fig. 4 is a sectional view on the line $\alpha\alpha$ of Fig. 2. Fig. 5 is a fragmentary view of the right hand shade 20 roller holder. Fig. 6 is a front elevation of the base plate. Fig. 7 is a front elevation of the way plate. Fig. 8 is a front elevation of the blank for the way plate. Fig. 9 is a view corresponding to Fig. 1 and on the 25 same scale of a modification of our shade roller holder as applied to the inside of the window casing and at the lower part thereof. Fig. 10 is a side elevation on an enlarged scale of one of the shade roller brackets shown in Fig. 8. Fig. 11 is a similar view of the same and in a different position.

Our curtain and shade roller supporter comprises a pair of individual holders, respectively a left holder 10 and a right holder 40 11 suitable for being secured to the window casing 12 and having adjustable means for supporting a shade roller 13 and removable and adjustable means for supporting a pole 14 for a curtain.

45 The means for supporting the shade roller 13 comprise a left shade bracket 15 and a right shade bracket 16 and the means for supporting the curtain pole 14 comprises a pair of curtain brackets 17 and these means are supported in pairs on each side on a common base 18. The curtain brackets 17 and the means for supporting the same are similar to those shown and described in a companion application Serial No. 774,804, filed 50 55 June 20, 1913. The left shade bracket 15 is provided with a slot 19 and the right shade

bracket 16 is provided with a hole 20 and which slot and hole are suitable for receiving the ends of the shade roller 13, otherwise, the left and right shade brackets being 60 quite similar.

The base 18 comprises an elongated rectangular structure having a way 21 extending laterally along the body portion thereof, and is composed of a base plate 22 and a way plate 23. The base plate 22 comprises a rectangular plate, having holes 56 along the lateral edges for holding screws and provided along the body portion with a longitudinal slot 24 and with a plurality of perforations 25 on each side of the slot 24, shown as four in number, two above and two below the said slot. At the outer end the base plate 22 is provided with a platform 26 provided with studs 27 for removably receiving the curtain bracket 17 precisely as shown in the companion application already mentioned. The way plate 23 as shown in the blank in Fig. 8 is a flat plate corresponding in length to the body portion of the 70 base plate 22 inward from the platform 26 and has a slot 29 corresponding to the slot 24 in the base plate 22 and has integral pins or lugs 30 extending outwardly from the upper and lower edges and corresponding 75 in number to the perforations 25, and the said plate 23 is bent downward along the upper and lower edges to a shallow U shape and suitably for the lugs 30 to register with the perforations 25 and to provide a space suitable to constitute the way 80 85 90 95 21 between the front body portion 31 and the opposed portion of the back plate 22. After the way plate 23 is placed in the position described the lugs 30 are headed over as shown in Figs. 3 and 4 and these thereby serve to secure the said way plate 23 to the base plate 22.

The shade brackets 15 and 16 comprise each a base arm 32 and shade roller arm 33 100 at right angles thereto, the latter having the slot 19 for the left side and the hole 20 for the right side. The base arm 32 is a sliding fit for the way 21 and is provided with a hole 34 in which is positioned a clamping 105 screw 35. The clamping screw 35 has a flat sided head 36 positioned in the slot 24 in the base plate 22 and having the flattened sides thereof engaged with the side walls of the said slot. The body portion of the 110 clamping screw 35 extends through the hole 34 and also the slot 29 in the way plate 23

and is provided on the forward end with a clamping nut 36 that bridges the slot 29 and engages with the front face of the body portion 31 of the way plate 23, and serves therefore to clamp the shade bracket in the position to which it may have been set along the slot 29. As described, the head 36 of the clamping screw 35 is housed in the slot 24 in the base plate 22 and the clamping screw 35 travels with the base arm 32 of the shade bracket as the same is moved along the base, and the clamping screw 35 and nut 36 serve to clamp the base arm 32 to the way plate 23 when in the clamped or locked position.

15 When used at the lower part or sill of the window casing and on the inner side as shown in Fig. 9, the shade bracket 15^a having the slot 19^a is used at the right and the shade bracket 16^a having the hole 20 is used 20 at the left and when used in this position we prefer to provide a special construction for the slotted bracket 15^a, as shown in Figs. 10 and 11. In this construction the shade arm 33^a stands vertically and upright and the slot 19^a extends vertically and has an entrance way or mouth 37 at one side and at the lower end of the said slot 19^a. The arm 33^a is fixed and we provide a closure for the said mouth 37 in the form of a movable member or slide 38. The said movable member 38 is in the form of a plate, pivotally connected by its lower end to the fixed arm 33^a by the pivotal pin 39 which is below the slot 19^a and suitable to swing toward and 35 over and away from the mouth 37. The upper end of the slide 38 is cut away on the inner face as shown at 39 to provide a shoulder 40 suitable for a rest for the flat end 41 of the shade roller, and at the same time to 40 provide an edge 42 practically flush with the corresponding edge 43 of the slot 19^a. In cutting away the slide 38 as described to form the shoulder 40 and the edge 42 a lip 44 is left integral with the slide 38, and 45 which is bent over suitably to engage in the closed position with the edge 43 and thereby lock the slide 38 in the closed position. The shoulder 40 is positioned in approximately horizontal alinement with the upper 50 wall of the mouth 37, and because of this any twisting or torsional strain on the part of the flat end 41 of the shade roller is transmitted directly to the walls of the slot 19^a in the fixed arm 33^a and no part of this is 55 brought to bear against the slide 38. Accordingly, the shade roller bracket shown in the said Figs. 9, 10 and 11 provides a posi-

tive means for supporting and locking the flat end of the shade roller in any position and is of course of special utility under the 60 conditions shown in Fig. 9 or used in the reversed position from that or ordinary use for shade rollers. Under the conditions shown in the said Fig. 9 the curtain bracket 17 is generally dispensed with and the platform 26 is accordingly dispensed with and the shade roller arms are positioned on the outer side of the clamping screws 35.

We claim as our invention:—

1. A shade roller supporter comprising a 70 pair of plates consisting of a front plate and a rear plate secured together in spaced relation and having slots in registration, a shade bracket extending through the said slot in the front plate and having a supporting arm 75 bridging the same, a screw extending through the said supporting arm and slot in the front plate and having a nut at the front end, the head of the said screw being positioned at the rear of the said supporting 80 arm and having flat side portions, the portions of the said rear plate on each side of and adjacent the slot therein serving to cover and inclose the lateral edge portions of the said supporting arm, the edge walls of the 85 said slot in the rear plate being in engagement with the said flat side portions of the said head of the screw suitably to prevent rotative movement thereof, and the said rear plate extending outwardly relatively to the 90 said front plate, and having screw holes, whereby the said rear plate serves as a base plate for the supporter, co-operates in housing the supporting arm of the shade bracket, and prevents rotative movement of the 95 clamping screw.

2. In a shade roller supporter, a shade bracket for the flat end of the shade roller comprising a fixed member having a slot and a mouth opening laterally at one end thereof, and a slide pivotally connected to the said fixed member and suitably positioned to close the said mouth, and the said slide having a shoulder suitable for supporting the shade roller, and a lip on the said slide 105 suitable for engaging with one of the walls of the said slot and to serve as a latch to hold the said slide in the closed position.
